(57) **CLAIM**

The ornamental design for a ring pendant, as shown and described.

DESCRIPTION

FIG. 1 is a perspective view of a first embodiment of a ring pendant showing our new design;

FIG. 2 is a front elevational view thereof, the rear elevational view is identical to the front;

FIG. 3 is a left side elevational view thereof, the right side elevational view is identical to the left side;

FIG. 4 is a perspective view of a second embodiment of FIG. 1;

FIG. 5 is a front elevational view thereof, the rear elevational view is identical to the front;

FIG. 6 is a left side elevational view thereof, the right side elevational view is identical to the left side;

FIG. 7 is a perspective view of a third embodiment of FIG. 1;

FIG. 8 is a front elevational view thereof, the rear elevational view is identical to the front;

FIG. 9 is a left side elevational view thereof, the right side elevational view is identical to the left side;

FIG. 10 is a perspective view of a fourth embodiment of FIG. 1;

FIG. 203 is a front elevational view thereof, the rear elevational view is identical to the front; and,
FIG. 204 is a left side elevational view thereof, the right side elevational view is identical to the left side.
